UNITED STATES PATENT OFFICE.

JAMES R. GROVES, OF DENVER, COLORADO, ASSIGNOR TO THE HERR DUMP CAR COMPANY, OF DENVER, COLORADO.

DUMP-CAR-DOOR-OPERATING MECHANISM.

No. 857,521.

Specification of Letters Patent.

Patented June 18, 1907.

Application filed June 1, 1906. Serial No. 319,722.

To all whom it may concern:

Be it known that I, JAMES R. GROVES, a citizen of the United States, residing in the city and county of Denver and State of Colorado, have invented certain new and useful Improvements in Dump-Car-Door-Operating Mechanism; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to mechanism designed to operate the discharge doors of dumping cars, and more particularly to a winding construction, by the use of which the released or opened doors can be quickly and with moderate manual exertion raised and carried to the closed position. The operating attachments are all disposed upon one end of the car, permitting the operator to release and rewind the doors without being required to leave his position, in manipulating the construction, thus greatly expediting the work; I furthermore require no separate or special tools or attachments, as wrenches, keys, etc.

In the accompanying drawings, the attachment is shown as being used in conjunction with longitudinally disposed, bottom discharge doors.

The construction of doors shown in the drawings is of special design, their several hinge-bar ends upon both their outer and inner longitudinal edges being adapted to coöperate with separable hinge-locking devices suitably secured to the body of the car, thereby permitting the release of the door from either the inner or outer edge, and the consequent discharge of the cargo either inwardly or outwardly as may be required. This construction of door fastening is similar to that shown and claimed in application, Serial No. 315,265 filed by Herbert T. Herr, May 4th, 1906. My construction is especially adapted to meet the requirements incident to the raising and closing of these inner and outer releasable doors.

The attachment is of simple and durable construction, having but few parts, which can be readily installed and effectually and reliably operated.

Reference is to be had to the accompanying drawings forming a part of this specification, in which:

Figure 1 is a cross section, all of the right half, and the upper part of the left half of which is taken upon section line $s-s$, of Figs. 2 and 3, the portion of the left half below the broken line being on section line $U-U$ of the same figures. In this figure the left hand door E is shown in the raised or closed position, and the right hand door F in open position, the inner separable hinge-locking devices H being released. I indicate by broken lines in the figure the several positions into which the doors may be dropped from any of which my winding attachment is operative, and will return the doors to the closed position. Fig. 2 is a plan view of the construction mounted upon and adjacent to the operative end of the car, the sloping end floor of the same being cut away approximately upon section line $V-V$ of Fig. 3, to more clearly show the parts. The position of the discharge doors in this figure being the same as shown in Fig. 1. Fig. 3 is a longitudinal section of a portion of a car equipped with my construction, which is shown principally in side elevation, the view being taken approximately on section line $X-X$ of Fig. 2. In this figure the construction is shown with the discharge door E in closed position, corresponding with the left hand door of Fig. 1. The released, outward discharge position of the door is shown in broken lines. Fig. 4 is an inverted plan view of a detail portion of the construction attached to the discharge door. Fig. 5 is an enlarged scale, detail cross section of a part of the door construction, taken on section line $Y-Y$ of Fig. 6. Fig. 6 is an enlarged scale detail side elevation of the construction corresponding with Fig. 5. Fig. 7 is a reduced scale longitudinal section of the car body taken on line $x-x$ Fig. 2, in which is shown an alternative construction of my attachment.

Similar reference characters throughout the description indicate corresponding parts in the several figures.

In the drawings, I illustrate in a general way a construction of dumping car body having an A-shaped built up central longitudinal truss-beam A, side channels B, B, bolsters C, C, sloping end floors D, D, and two longitu-

dinally hinged discharge doors E and F, both hinged upon their respective inner and outer edges, to separable hinge-locking devices G, G and H, H mounted upon the central and side channels beams of the car body as shown. Duplicate winding constructions coöperating respectively with each door E and F are suitably mounted upon the car body, in a vertical plane substantially on the longitudinal center of each discharge door. These comprise a cable, chain, band or other suitable construction 2, the forward end of which is secured to a vertical winding shaft 3, which is suitably securely mounted in upper and lower brackets or bearings 4, 4, upon the main car bolster C, as shown. The winding chain 2 is secured to the shaft 3 between these bearings as at 2^a. A ratchet 5 is keyed upon the winding shaft 3, immediately above the upper bearing 4, adjacent to and coöperating with which is a pawl 6 pivotally mounted on the same bearing. Onto the upper end of each winding shaft is secured a hand wheel 7. Transverse sheave - supporting beams 8, 8 are mounted upon the car body adjacent to the forward end of the discharge doors, and similar transverse supporting beams 9, 9 are mounted adjacent to the rear end of the doors. A sheave 10 carrying the cable 2, is mounted in a swiveling yoke 10^a jointedly hung upon the center of the supporting beam 8. Any required number of sheaves 11, 11, 11 are mounted upon the under side of the discharge doors E and F, upon the longitudinal centers of the same, with one each adjacent either end of the door. These sheaves are mounted in a construction clearly shown in the enlarged scale detail Figs. 5 and 6, comprising two longitudinally disposed angle iron beams 12, 12 of the same length as the doors, securely bolted to the several transverse door hinge irons and being spaced sufficiently to admit the sheaves which are secured upon axial bolts 11^a between the depending angles 12^a of the beams.

Transverse supporting braces 13, are bolted to the door hinge irons and sheave supporting beams over each sheave, forming a supporting brace against lateral forces upon the sheaves as when raising the door F from the fully opened position shown in Fig. 1. This brace also forms a guard iron 13^a beneath the sheaves 11.

A swivel ring 14 is jointedly mounted upon the transverse supporting beams 9, 9 to which is secured the socket end 2^b of the winding cable 2. In the drawings this winding cable is shown as being fitted with a loop-socket 2^c upon the forward end, which is secured to the end of a short section of winding chain 2^d which is bolted to and wound around the shaft 3. From the winding shaft 3, the cable 2 is carried back over the supporting sheave 10, then down and under the door sheaves 11, and up to the rear support 14.

This cable moves freely backward or forward in a longitudinal direction between the door sheaves 11 and guard irons 13^a. A chain throughout can be used instead of the steel cable as shown, if preferred.

By referring to Fig. 3 it will be seen that the cable supporting eye 14, and the supporting sheave 10 are disposed in a horizontal plane somewhat above the plane of the discharge door sheaves, thus forming in the cable a flexible truss member, which when wound taut carries the door up to the closed position where it can be positively secured by moving the separable hinge members into engagement.

An important function arises consequent upon the using of this longitudinally, centrally applied, flexible, trussed cable winding member in conjunction with this specific construction of inwardly or outwardly releasable hinge, and dropping door, which I believe to be entirely new, inasmuch as the construction permits the door to be dropped partly or entirely open in either direction, while the winding cable is at all times disposed beneath the same, from either of which position simply rewinding the cable without special or supplemental adjustments carries the open door up into the closed position.

It will also be seen by reference to the right half of Fig. 2 showing in plan the open door F, and adjacent open door-space, and also by reference to Fig. 3, where the sloping sections of the winding cable pass beneath the ends of the door, clear of the same, that this winding cable or chain construction does not pass across the discharge opening, nor in any degree obstruct the same. This is an important feature in practice inasmuch as constructions requiring the winding chains to pass across the discharge opening frequently have such chains broken away by the impact of heavy masses of discharging cargo. There is danger also of their being rendered inoperative because of in transporting damp or wet cargoes in freezing weather such chains are liable to become inoperatively embedded in the frozen mass.

As will be seen by referring to Fig. 3 the equipment beneath the discharge doors is comparatively simple and very compact, thereby reducing to a minimum the damage liable to result from "stripping" the car body equipment, in an accident. If damaged the repairs call for no such expensive work, as re-forging, lining-up or possibly replacing expensive shafting, gearing, levers etc.

An alternative construction of my attachment is shown in Fig. 7, wherein the flexible device is attached at the respective ends to winding shafts 3 and 3^a by sections of winding chains 2^d and 2^e, a supporting sheave 14^a and transverse beam 9^a replacing the swivel ring 14 and transverse beam 9^a. By this ar-

5 arrangement it will be understood that the door can be raised by winding with either shaft 3 or 3^a, while the inoperative shaft fulfils the function of an anchorage for the unwound end of the cable 2.

Having thus described my invention, what I claim is:

1. In a dump car provided with a hinged dumping door, the combination of means for closing the door comprising a flexible device fixedly connected with a stationary part of the car at one end of the door, extending underneath the latter in a line parallel with its hinging axis, a guide connected with the door and engaged by the flexible device, and means connected with the flexible device whereby the latter may be taken up and paid out at will.

2. The combination in a dump car having a hinged dumping door, of a flexible device passing underneath the door in a line parallel with its hinging axis, the said device being fixedly connected with the car at one end of the door, and means located at the opposite 25 end of the door with which the flexible device is connected for manipulating the latter for door-closing and releasing purposes.

3. In a dump car provided with a dumping door hinged at its opposite longitudinal edges, means coöperating with the hinging member to release the door at either edge for dumping purposes, and a flexible device extending underneath the door and centrally disposed, whereby as the flexible device is 35 properly manipulated the door may be raised to the closed position.

4. A dumping car provided with a hinged dumping door, and means coöperating with the hinge members to release the door for dumping purposes, and a flexible device fixedly connected with the car at one extremity of the door, and extending underneath the same, and means connected with the flexible device at the opposite extremity of the door device whereby the flexible device may be wound up or paid out as desired, the flexible device being entirely independent of the releasing means.

5. In a dump car, the combination with a hinged dumping door, of a flexible device connected with the car at one extremity of the door parallel with the line of its hinging axis, passing underneath the door, means connected with the flexible device at the opposite extremity of the door for manipulating the said device for door-closing and releasing purposes, and anti-frictional guides secured to the under surface of the door and engaged by the flexible device.

6. The combination with a vehicle body having a dumping door, of a flexible device connected with the car at one extremity of the door and extending underneath the same, means connected with the flexible de-

vice at the opposite extremity of the door for 65 manipulating the flexible device, the under side of the door being provided with a channel, and anti-frictional means supported by the walls of the channel and engaged by the flexible device.

7. The combination with a vehicle body provided with a dumping door, of a flexible device extending underneath the door, a swiveled socket in which one extremity of the flexible device is anchored, a sheave located at the opposite extremity of the door and engaged by the flexible device, and a swiveled holder for the last named sheave.

8. The combination with a vehicle body having a dumping door, of a flexible device 80 extending underneath the door, means for holding the flexible device at one extremity, means connected with the opposite extremity of the flexible device for manipulating the latter for door-closing purposes, sheaves journaled in the door on the under side and engaged by the flexible device, and braces passing underneath the sheaves whereby the flexible device is prevented from leaving the sheaves.

9. The combination with a vehicle body provided with a door hinged at both longitudinal edges, means coöperating with the hinged members for releasing the door at either hinged edge, and a flexible device extending underneath the door, means for retaining the flexible device in operative position underneath the door, means for anchoring the flexible device at one extremity, and means connected with the opposite extremity of the flexible device for manipulating the latter for door-closing purposes.

10. The combination with a vehicle body having a door hinged at both longitudinal edges, means coöperating with the hinged 105 members of the door for releasing the latter to allow the door to open at either hinged edge, a flexible device extending underneath the longitudinal center of the door, the door being provided with guides for the flexible 110 device whereby it is maintained in operative relation with the door, and means connected with the flexible device for manipulating the latter for door-closing purposes.

11. The combination with a vehicle body 115 having a central longitudinally disposed beam, hinged dumping doors located on opposite sides of the said beam, means coöperating with the hinged member of each door for releasing the door to allow it to open at 120 its hinged edge, and a flexible device extending underneath each door parallel with the line of its hinging axis, and means connected with the flexible device for manipulating the latter for door-closing purposes.

12. The combination with a vehicle body provided with a dumping door, means for releasing the door to allow it to open for

- dumping purposes, a flexible device extending underneath the door, parallel with its hinging axis, means connected with the flexible device and located in a plane above the plane of the door, whereby the flexible device is supported at the opposite extremities of the door, and means connected with the flexible device for manipulating the latter for door-closing and releasing purposes.
13. The combination with a vehicle body provided with a hinged dumping door, means coöperating with the hinged members of the door for releasing the door to allow it to open at its hinged edge, a flexible device extending underneath the door parallel with its hinging axis, means for anchoring the flexible device at one extremity of the door, and winding

means connected with the flexible device at the opposite extremity of the door.

14. The combination with a vehicle body having a dumping door, of a cable connected at one extremity of the door, extending underneath the latter parallel with its hinging axis, a chain connected with the opposite extremity of the cable, and a winding shaft with which the chain extremity of the cable is connected.

In testimony whereof I affix my signature in presence of two witnesses.

JAMES R. GROVES.
